Primary Examiner — Jennifer L Rempfer(74) *Attorney, Agent, or Firm* — Law Offices of Steven W. Weinrieb(57) **CLAIM**

The ornamental design for a shaped pillow, as shown and described.

DESCRIPTION

FIG. 1 is a front, left side, top perspective view of a shaped pillow showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof; and,

FIG. 8 is an enlarged detailed view of the encircled region 8 shown in FIG. 1.
The broken lines form the bounds of the detail view and form no part of the claim.**1 Claim, 8 Drawing Sheets**FIG. 1
